UNITED STATES PATENT OFFICE.

LE ROY COPLIN, OF WINDBER, PENNSYLVANIA.

STOP MECHANISM FOR TALKING MACHINES.

1,402,574.

Specification of Letters Patent.

Patented Jan. 3, 1922.

Application filed March 16, 1921. Serial No. 452,697.

To all whom it may concern:

Be it known that I, LE ROY COPLIN, a citizen of the United States, residing at Windber, in the county of Somerset and State of Pennsylvania, have invented certain new and useful Improvements in Stop Mechanism for Talking Machines, of which the following is a specification.

This invention relates to stop mechanism for talking machines to automatically stop the machine when the record is finished and is designed as an improvement on an invention of this character shown and described in my application Serial Number 416,227 filed October 11, 1920.

The primary object of the invention is to provide an automatic non-set stop for talking machines controlled exclusively by the motion of the tone arm and which requires no setting or attention by the operator.

Another object is to so construct such mechanism that the brake will be applied gently and smoothly to stop the turntable avoiding abrupt stoppage of the machine and the injurious effects incident thereto.

Another object is to provide a stop of this character which can be used on any talking machine not employing a gear driven tone arm such as the Edison, without in any way altering the machine; which is simple in construction and cheaply manufactured and which operates simply and positively.

Another object is to provide a brake applying device for talking machines so constructed and connected with the tone arm that the brake can only be applied when the tone arm ceases to move which occurs when the last thread of the record is reached.

Another object is to so construct and connect such a stop that the tone arm may be lifted and moved outward beyond the turntable to provide for the change of a record without releasing the brake, which release is effected by the moving inward of the tone arm into playing position on the record.

With these and other objects in view, the invention consists in certain novel features of construction as hereinafter shown and described and specifically pointed out in the claims, and in the drawings illustrative of the preferred embodiment of the invention.

In the accompanying drawings:

Figure 1 represents a top plan view of a

talking machine turntable with the tone arm shown lifted off the record to provide for the changing thereof, a part of said table being broken out to disclose the attachment constituting this invention, the parts of the attachment being in the position assumed when the record has been completed and brake applied.

Fig. 2 is an enlarged detail sectional view taken on the line 2—2 of Fig. 1, and,

Fig. 3 is a detail plan view of the portion of a bar or plate constituting a part of the friction connecting means between certain of the members.

In the embodiment illustrated a turntable T is shown mounted centrally on a post P and over which is mounted to operate a tone arm A carrying the reproducer R. These parts are of ordinary construction such as are usually found in talking machines employing disc records and form no part of the invention.

The attachment constituting this invention is mounted beneath the turntable T preferably on a metal plate 1^a to be screwed on the board B underneath the turntable, and comprises a small gear 1 mounted on the center post P which meshes with a larger gear 2 carrying on its upper face a friction washer 3 which is here shown in the form of a three pointed star, one point of which carries on its outer end a depending pin or stud 4 for a purpose presently to be described, the point or finger 3^a which carries the stud 4 being flush with the top of the washer 3 while the other points are offset downwardly and have frictional contact with the gear 2.

The top of the cabinet or the board B is mortised out as shown at 7 to receive the gears 1 and 2 which are positioned therein with their faces flush with the upper face of the board B, to provide for the use of a flat plate 1^a to bear throughout its length against the member B as is shown clearly in Fig. 1.

A plate 5 is mounted loosely at one end on a screw bearing 6 at a point to the left of gear 2. This plate 5 has a transversely arranged slot 8 intermediate its ends through which a headed stud 9 projects, said stud being carried by the plate 1^a. This stud and slot operate to limit the swinging

movement of plate 5 in opposite directions, which movement is accomplished by means presently to be described.

The plate 5 is also provided on its inner edge with an upturned inclined lip 10 for cooperation with the stud 4 for a purpose presently to be described and which corresponds to and performs the same function of the lip 10 shown in the application above referred to.

A brake 20 is carried by one end of an L-shaped or bell crank lever 21 fulcrumed at its other end to the plate 1^a as shown at 22 and to the elbow of which is pivotally connected one end of a bar 23 as shown at 24. The brake 20 is positioned adjacent the perimeter of the turntable T and is movable radially toward and away from the edge of said table on the application or release of the brake. The inner end of the bar 23 carries a longitudinally slotted head 25 through the slot 26 of which passes a headed stud 27 carried by the free end of the plate 5. The terminal of head 25 has an upstanding lug 29 which is adapted to be positioned in the path of the stud 4 when the plate 5 is at the limit of its innermost movement as shown in Fig. 1, the slot 26 in the head 25 permitting the brake bar 23 to be moved longitudinally for applying and releasing the brake, the application of the brake being effected by the engagement of the pin 4 with the lug 29 on said head and which occurs only when the tone arm ceases its movement.

A coiled spring 30 is connected at one end with the bar 23 and at its other end with the plate 1^a and operates to normally move the bar outward to hold the brake 30 in inoperative position and to return it to this position when released and the machine is in operation.

An arm 15 is fixedly mounted at one end to the base of the tone arm A and extends radially and downwardly therefrom having pivotally connected at its free end a bar or plate 11, the free or front end of which is slotted longitudinally as shown at 13 and has a rearwardly extending spring tongue 14 forming one wall of the slot 13 throughout a portion of its length and which cooperates with friction discs 16 and 17 carried by a stud 18 extending upwardly from plate 5 through the slot 13. A coiled spring 19 is mounted on the stud 18 between the upper disc 16 and a nut 19^a carried by the stud 18 which controls the frictional connection between the plate 5 and the bar 11.

The pivotal connection between the front end of the arm 15 and the rear end of the bar 11 is sufficiently loose to provide for the unsteady motion of the tone arm while playing a record without affecting the stopping mechanism.

In the use of this attachment it being applied as shown in Fig. 1, the inward or cen-

terward movement of the tone arm A will operate to move the free end of the arm 15 outward carrying with it the bar 11 and through the frictional connection between said bar and plate 5 will operate to swing the plate 5 outwardly on its pivot 6 a sufficient distance to move the lug 29 on the brake bar 23 out of the path of the stud 4 carried by the friction washer or disc 3. The movement of the tone arm in the opposite direction moves the arm 15 inward causing the bar 11 to slide between the friction washers 16 and 17 and to exert sufficient force on the plate 5 to move it inwardly so that when the pin 4 is engaged with the lug 29 for locking the brake in operative position the outward movement of the tone arm will not release it.

Five turns of the record will move the tone arm A five threads nearer to the center of the record and during this movement the gear 2 will make one revolution. The revolution of the gear 2 correspondingly rotates the friction washer 3 and on each revolution thereof the stud 4 engages the lip 10 of plate 5 which lip being bent at an angle as shown causes the plate 5 to be pulled inward while the impelling force of the tone arm operates to move the plate 5 including the lip 10 and the brake bar carried lug 29 outward so that said lug 29 will be out of the path of the stud 4 and prevent application of the brake while the record is playing or the tone arm is moving inward. It will thus be seen that the tone arm will swing the plate 5 outwardly while the pin 4 engaging the lip 10 will swing it inwardly. The backward or outward movement produced by the action of the tone arm on plate 5 causes the pin 4 to escape engagement with the lug 29 on the brake bar 23 thereby avoiding the application of the brake during the playing of a record, it being necessary to provide this oscillatory movement of plate 5 so that when the tone arm ceases to move at the end of a record it will have no effect on plate 5 so that the lug 29 will be positioned in the path of the stud 4 and will be engaged by said stud on the turning of the gear 2 which will cause the brake bar 23 to be moved longitudinally inward thereby applying the brake and stopping the machine. The friction washer 3 which carries the stud 4 will permit the brake to be applied gently and smoothly and avoid abrupt stoppage of the machine.

In the operation of this attachment when the brake is applied by the stoppage of the tone arm in the manner above described and as shown in Fig. 1 the reproducer R is lifted and moved outward beyond the perimeter of the turntable and the record mounted thereon to permit changing of the record and this outward movement as above described does not release the brake because the inward

movement of the arm 15 also moves the plate or bar 11 inward and the plate 5 connected therewith inward to hold the brake bar carrying lug 29 engaged with the pin 4.

5 After changing the record or when it is desired to repeat the one already on the machine the tone arm is moved inward toward the record and this movement operates through arm 15 and bar 11 to swing the plate 5 outward and release the lug 29 from the pin 4 thereby releasing the brake which under the tension of the coiled spring 30 will move outward away from the perimeter of the turntable and permit said table to 10 rotate carrying with it the record to be played.

From the above description it will be obvious that if the reproducer is removed from the record by the operator either before 20 or after the record is played or during the playing of the record the turntable will stop without any attention from the operator. This is due to the fact that there is no means for swinging outwardly the plate 5 and permitting the brake carried lug 29 to be retracted except when the tone arm is being moved centerward such as occurs during the 25 playing of a record.

The preferred embodiment of the invention 30 is disclosed in the drawings and set forth in the specification, but it will be understood that any modifications within the scope of the claimed invention may be made in the construction without departing from the 35 principle of the invention or sacrificing any of its advantages.

What is claimed is:

1. In an automatic non-set stop for talking machines, the combination with a tone 40 arm; of a brake normally held in inoperative position, means for applying said brake, and a slidable friction connection between said tone arm and one member of said brake applying means operable on the inward movement of the tone arm to prevent application of the brake.

2. In an automatic non-set stop for talking machines, the combination with a tone arm; of an arm fixed at one end to said tone 50 arm, a bar pivoted at one end to the free end of said arm, a brake normally held in inoperative position, means for applying said brake, and a slidable friction connection between said bar and one member of 55 said brake applying means operable on the inward movement of the tone arm to prevent application of the brake.

3. In an automatic non-set stop for talking machines, the combination with a tone 60 arm; of a brake carrying bar normally held in inoperative position, a member mounted for oscillatory movement and having a pin and slot connection with said brake bar, a rotary member, means on said rotary member and said bar for engaging when the os-

cillatory member is swung in one direction and a sliding friction connection between said oscillatory member and said tone arm whereby said member is swung to prevent engagement of the rotary member with the 70 brake bar when the tone arm is moved inwardly.

4. In a stop of the class described, the combination with a tone arm; of a turntable, a post connected to rotate said table, a reciprocating brake carrying bar, a spring to hold said bar with the brake normally in inoperative position, rotary means operable by the turntable operating means to engage said bar and move it against the tension of the 80 spring to apply the brake, and slidable friction means controlled by the tone arm to move the bar out of the path of said rotary means while the tone arm is in motion.

5. The combination with a tone arm and a 85 turntable; of a brake for said turntable, a bar connected to operate said brake, a plate mounted to swing horizontally under said turntable, a pin and slot connection between said plate and bar to provide for the swinging 90 of the bar with the plate and permit the bar to slide longitudinally on the plate, means for limiting the swinging movement of said plate, a rotary element mounted to engage said plate and swing it in one direction to bring the brake bar in the path of 95 said element, a bar having sliding friction connection with said plate, an arm fixed to said tone arm, said arm and bar being pivotally connected.

6. An attachment of the class described comprising a base plate for mounting on a talking machine below the turntable thereof; an L-shaped lever fulcrumed at one end on 100 said plate and having braking means on its other end, a brake rod pivoted at one end to the elbow of said lever, a coiled spring connected to normally hold the brake inoperative, a plate mounted to swing horizontally on said base plate, means for limiting the swinging movement of said plate, a pin and slot connection between the free end of 105 said plate and said brake rod, an arm to be fixed at one end to the tone arm, a bar pivoted at one end to the free end of said arm and having a sliding friction connection with said pivoted plate, whereby the plate is swung in one direction by the tone arm, 110 rotary means to engage said plate and move it in a direction opposite to that in which it is moved by said arm whereby said brake bar is positioned in the path of said rotary means, the tone arm moving said bar out of 115 said path while said tone arm is in motion.

7. The combination with a tone arm and a turntable; of a reciprocating brake carrying bar, a spring to hold said bar with the brake normally in inoperative position, a plate pivoted to swing horizontally under 120 said turntable, a connection between said 125

plate and arm whereby the bar swings with the plate, means for limiting the swinging movement of said plate, a rotary element mounted to engage said plate and swing it in one direction to bring the brake bar in the path of said element, a bar having a pin and slot connection with said horizontally swinging plate, means for producing fric-

tional connection between said pin and the walls of said slot, and means for gradually increasing the friction between these members on the forward movement of said bar.

In testimony whereof, I affix my signature hereto.

LE ROY COPLIN.
